Patented Mar. 10, 1914.

UNITED STATES PATENT OFFICE.

SPENCER G. NEAL, OF LOS ANGELES, CALIFORNIA, ASSIGNOR TO CALIFORNIA VALVE AND AIR BRAKE COMPANY, OF LOS ANGELES, CALIFORNIA, A CORPORATION OF CALIFORNIA.

COMPENSATING VALVE.

1,089,576.

Specification of Letters Patent. Patented Mar. 10, 1914.

Application filed July 29, 1913. Serial No. 781,835.

To all whom it may concern:

Be it known that I, SPENCER G. NEAL, a citizen of the United States, residing in the city of Los Angeles, State of California, have invented a new and useful Compensating Valve, (Case B,) of which the following is a specification.

The compensating valve which forms the subject matter of this invention is adapted to a great variety of uses, but is more particularly intended as a means to regulate the supply of air under pressure to air braking systems for railways.

The present invention has for one of its principal objects the provision of an improved compensating valve that will not fail to maintain a predetermined pressure in a train pipe, such train pipe pressure in present practice being reduced (not maintained), when leaks occur in the train pipes or fittings.

This compensating valve will operate successfully in conjunction with the engineer's valve of present braking systems with but slight alteration of said valve. Moreover, this compensating valve automatically maintains a predetermined pressure in a train pipe during service, lap, and running positions. In this particular this invention is an improvement over the feed valve in use at the present time, because said feed valve is capable of furnishing air to the train pipe in moderate quantities only, and only during such time as the engineer's valve is in running position.

Referring to the accompanying drawings, which illustrate the invention: Figure 1 is a vertical mid-section of this compensating valve. Fig. 2 is a plan view of a disk which is inserted in a well known braking valve to adapt the same to coöperate with this compensating valve. Fig. 3 is a view, the sectioned part of which illustrates certain changes in a well known engineer's valve to adapt same to coöperate with this compensating valve. Fig. 4 is a mid-section of the compensating valve, the valve operating parts being shown in a different position from that illustrated in Fig. 1. Fig. 5 is a diagrammatic view illustrating the application of this compensating valve to a well known air braking system.

Referring in detail to the drawings, 1 in a general way designates the compensating valve, (see Fig. 5) 2 the engineer's valve and

3 the main storage reservoir for supplying braking air to the train pipe.

The well known main supply pipe 4 leads from the storage reservoir 3 to the brake valve 2; a branch pipe 5 leads from the 60 brake valve 2 to the main train pipe 6. Pipe 4 may be provided with a well known cut-out valve 7. The brake valve 2 is connected with the usual equalizing reservoir 8 by means of an equalizing pipe 9. Pipe 5 is 65 provided with valve 11. In order to connect the compensating valve 1 with these well known parts, a supply pipe 12 is run from the reservoir pipe 4 to the compensating valve 1, said pipe 12 preferably being provided 70 with a cut-out valve 14; and an equalizing reservoir pipe 15 is run from compensating valve 1 to the equalizing reservoir 8 or to the pipe 9, which is in communication with the said equalizing reservoir 8. Said 75 pipe 15 is preferably provided with a cut-out valve 16; pipe 17 is also added to connect the compensating valve to the main tanks, but in practical operation the braking furnished with a cut-out valve 18. 80

The braking apparatus which has thus far been described, relates to the engine only and it is to this part of the braking apparatus of the train that this invention pertains, but in practical operation the braking 85 action on each car of the train is affected.

Referring now more particularly to Fig. 3, this view shows the well known engineer's brake valve altered somewhat in the sectioned portion to adapt the same to coöperate with this compensating valve.

22 is the usual train pipe piston chamber, the piston being removed therefrom, and a combined metallic and leather gasket or disk 23 being placed over said chamber 22 95 to make an air tight seal between the equalizing chamber 24 and said train pipe chamber 22. The reason for inserting said gasket 23 is that the well known piston (not shown) which ordinarily occupies chamber 100 22, would not make an absolutely air tight closure between the chambers 22 and 24. The main reservoir supply passage 25, the train pipe connection 26, and the train pipe supply passage 27 are not altered from the 105 standard equipment, but equalizing discharge valve outlet 28 is closed by screw plug 29.

Referring now in detail to the construction of the compensating valve shown in sec- 110

tion in Figs. 1 and 4, the casing for said valve preferably comprises a spacing ring 31, an upper cap 32, and the lower cap 33; said caps 32 and 33 being clamped against opposite sides of the said ring 31 by means of bolts 34, having nuts 35. The inner peripheral portion of the chamber formed by said ring and caps is provided with two tapered recesses 36 and 37 to provide for the proper operation of the diaphragms 38 and 39, which are respectively placed next to the upper cap 32 and lower cap 33. Between said diaphragms 38 and 39 is placed a hollow spacing device 41, having an upward extension 42 around which the diaphragm 38 extends, the diaphragm supporter or clamping nut 43 being screwed upon said extension 42 to hold said diaphragm 38 in place. The lower diaphragm 39 likewise is fitted around an extension 44 and is held in place by the lower clamping nut 45.

Around the whole spacing device 41 is an annular vent chamber 46 which communicates by means of ports 47 with the central valve cage 48. Within said valve cage 48 extends winged portion 49 of the release valve 51, which when opened by decrease of pressure in equalizing chamber 50 permits air to pass from the train pipe chamber 52 through valve cage 48, ports 47 and annular chamber 46 out through the vent passage 53 to the outside atmosphere. Formed in one piece with the valve 51 is a downward winged extension 54 provided at its lower end with a supply valve 55. Said winged portion 54 is guided by an annular extension or sleeve 56 formed within the chamber 52. Pipe 12 leads from the main reservoir 3 (see Fig. 5) to supply passage 57, thence to the valve chamber 58 beneath supply valve 55. The lower end of chamber 58 is closed by a stop plug 59 which limits the downward movement of the supply valve 55 and parts connected therewith. Lock nut 60 holds plug 59 in place. The upward movement of the diaphragm device as a whole is limited by a screw bolt 61 which is adjustably retained by a lock nut 62. Disk 23 (see Figs. 3 and 4) is provided with an aperture 25^a to register with supply passage 25, with an aperture 26^a to register with train pipe supply passage 27, and with the well known equalizing passage 70. These openings furnish outlets to all the passages and ports of the well known engineer's brake valve, the piston chamber alone being closed at its upper end and thereby separated from chamber 24.

Operation: Before describing the operation it should be remembered that this compensating valve performs all the functions of the equalizing discharge valve and its piston (said piston being dispensed with and removed from the piston chamber 22 of the engineer's valve, as already stated) and in

addition to such functions this compensating valve performs certain other functions which will hereinafter be described. The engineer's valve proper will perform all of its well known functions and maintain its various positions as before, viz., full release, running, service, lap, and emergency positions. The charging of the train pipe is caused, as is well known in present braking systems of standard type, by placing the engineer's valve in the full release position in order quickly to charge the train pipe, said engineer's valve being placed at the running position as in present practice, as soon as the desired maximum train pipe pressure has been obtained. The train pipe having thus been charged to the required pressure, and the equalizing reservoir 8 also being charged to an equality with the train pipe pressure, the result will be that the pressure in the equalizing chamber 50 which is in communication with the equalizing reservoir 8, will be the same as the train pipe pressure in the train pipe chamber 52 of the compensating valve, said chamber 52 being in direct communication with the train pipe through the pipe 17. With the pressure as just described, in order to make a reduction of the train pipe pressure, the brake valve 2 is placed in service position, thereby releasing air from the equalizing reservoir 8 to the atmosphere to any desired amount, and thus through pipe 15 releasing the pressure in the equalizing chamber 50 of the compensating valve below the pressure in the lower train pipe chamber 52 of said compensating valve. The result of said change of pressure will be to allow the excess pressure in chamber 52 beneath diaphragms 39, to raise the spacer 41 and parts connected therewith to the position shown in Fig. 1, thus opening the release valve 51 and venting train pipe air through the ports 47 and passages 53. When the train pipe pressure in train pipe chamber 52 has been reduced beneath the pressure in equalizing chamber 50 said spacer 41 and the parts directly connected therewith will move back to the lap position, thus closing the relief valve 51 and cutting off further escape of train pipe air to the atmosphere.

If, instead of reducing the pressure in equalizing reservoir 8, as has just been described, the engineer's valve was operated in such a manner as to raise the pressure in equalizing chamber 50 the result would be a reverse operation in the compensating valve, the pressure in equalizing chamber 50 exceeding that in train pipe chamber 52 and causing the diaphragm device to descend, thus forcing supply valve 55 away from its seat and allowing the air from the main reservoir to enter train pipe chamber 52 by way of passage 57 and pass thence through branch pipe 17 to the main train pipe 6.

It is evident that any reduction of pressure in the train pipe chamber 52 will operate the compensating valve in the same manner as an increase of pressure in the equalizing chamber 50. Such reduction may be caused by leaks in the train pipe and also by the operation of the triple valve to supply the desired amount of air to the brake cylinder for a service application. The adaptability of this compensating valve to furnish air pressure to the train pipe for all service applications when using the patented triple valve just referred to, eliminates entirely the necessity of the storage system during all service applications, and also reduces the element of time for the re-charging of reservoirs in which pressure has been reduced according to present practice by such service applications.

20 I claim:

1. The combination with a train pipe and an engineer's brake valve, of means to regulate the supply of air to the train pipe; said means comprising two diaphragms, a spacing device to rigidly connect said diaphragms to each other, there being an annular chamber communicating with the outer atmosphere between said diaphragms around said spacing device, there being also a valve chamber within said spacing device communicating with said annular chamber, the lower end of said valve chamber communicating with the train pipe chamber located beneath said diaphragm device, a release valve in said valve chamber to control release of air from the train pipe chamber to the outer atmosphere, and a supply valve formed as a downward continuation of said release valve to regulate the supply of air to said train pipe chamber.

2. The combination with a train pipe and engineer's brake valve, of means to regulate the supply of air to the train pipe; said means comprising a casing, a diaphragm

device dividing said casing into three separate chambers, one of said chambers being interior with respect to said diaphragm device, said interior chamber being at all times in communication with the outer atmosphere, a release valve to control communication with said interior chamber, and a supply valve rigidly connected with said release valve to control supply of air to said train pipe chamber.

3. A compensating valve comprising a casing, a diaphragm device dividing said casing into three chambers, the chamber on one side of said diaphragm device being an equalizing chamber and the chamber on the other side of said diaphragm device being a train pipe chamber, a vent chamber located interiorly of said diaphragm device, a valve chamber also located within said diaphragm device and communicating with said vent chamber, said valve chamber having a closed upper end and a lower end forming a valve seat, a valve having a winged portion within said valve chamber and a base portion to open and close the lower end of said valve chamber and a supply valve to control the supply to the train pipe chamber, said supply valve being a downward continuation of said release valve, downward movement of said diaphragm device first closing said release valve, and farther downward movement of said diaphragm device opening said supply valve to supply air to said train pipe chamber.

In testimony whereof I have hereunto signed my name in the presence of two subscribing witnesses at Los Angeles, in the county of Los Angeles and State of California, this 23rd day of July 1913.

SPENCER G. NEAL.
